METHOD AND APPARATUS FOR CONDITIONING METAL BODIES

James H. Bucknam, Cranford, and Edward Meincke, Roselle Park, N. J., and Theodore W. Eselgroth, Gary, Ind., assignors to The Linde Air Products Company, a corporation of Ohio

Application January 27, 1940, Serial No. 315,896

24 Claims. (CL 148—9)

The invention relates to metal conditioning and more particularly to an improved method and apparatus for thermochemically conditioning surfaces of ferrous metal bodies, such as slabs, billets, blooms and the like.

In the art of desurfacing a ferrous metal body, such as a steel billet, a heating flame is first directed against a portion of a surface from which metal is to be removed, to raise the metal to its ignition temperature. After the metal has attained this temperature, a stream of oxidizing gas is directed obliquely against the heated portion of the surface to effect a thermochemical reaction with the heated ferrous metal. The heating flame and oxidizing gas stream thereupon are moved relatively to said body and in a direction substantially parallel to the surface to remove a thin layer of metal therefrom, leaving a bright and clean new surface that is substantially free from defects such as seams, cracks, and the like.

When heating flames alone are used to raise a portion of surface metal to the ignition temperature to start a desurfacing operation, the pre-heating time may vary considerably. The pre-heating time for starting at a square cut end edge of a billet generally varies from twelve to thirty seconds for a cold billet and from three to eight seconds for a hot billet. However, it is often desirable to start the operation at a place other than at the edge of a billet, but it takes a much longer time to heat such a place to an ignition temperature, and excessive and undesirable gouging of the surface at such places often occurs when the oxidizing stream is applied to start desurfacing. Heretofore, the length of the pre-heating time has depended upon an operator's judgment, so a rather highly skilled operator has been required. Accordingly, in many instances, the partial desurfacing of a ferrous metal body has been difficult and expensive, and unsatisfactory results have been obtained.

The principal objects of this invention are to provide an improved method and apparatus for thermochemically conditioning the surfaces of ferrous metal bodies, such as blooms, billets, slabs, and the like, which method and apparatus shall minimize and substantially overcome the disadvantages discussed above. Other and more specific objects are: to provide an improved method and apparatus for substantially reducing the starting time and other difficulties involved in an operation for thermochemically removing a relatively wide and thin layer of metal from the surface of a ferrous metal body; to provide, in

such a conditioning method and apparatus, greater efficiency and uniformity when starting along a relatively wide zone of the surface to be treated, as well as greater efficiency of the succeeding portion of a desurfacing operation; to provide a surface conditioning method and apparatus which may be timed with greater precision and operated practically automatically from the beginning to the end of a pass to produce uniformly satisfactory results in less time and with less skilled operators than were required formerly.

The invention accordingly comprises the several steps and the relation of one or more of such steps with respect to each of the others, the apparatus embodying features of construction, combinations and arrangement of parts adapted to effect such steps, all as exemplified in the detailed disclosure hereinafter set forth.

For a fuller understanding of the nature and objects of the invention, reference should be had to the following detailed description taken in connection with the accompanying drawings, in which:

25 Fig. 1 is a fragmentary perspective view of a desurfacing machine embodying features of this invention;

Fig. 2 is a view, partly in section, of the work, and partly in rear elevation, illustrating the position of the starting rods after the desurfacing operation has started;

Fig. 3 is a view of a vertical section taken on line 3—3 of Fig. 1;

Fig. 4 is an elevational view, in section, of a modified form of apparatus;

Fig. 5 is an elevational view of a further modified form of apparatus;

Fig. 6 is an enlarged sectional view taken along the line 6—6 of Fig. 5 showing the construction and arrangement of the starting rod gripper, and

Fig. 7 is a wiring diagram of the electrical control apparatus whereby automatic operation of a desurfacing machine is obtained according to the invention.

45 In order to accomplish the removal of surface metal from ferrous metal bodies, such as from ingots, blooms, billets, and the like, for the purpose of eliminating checks, seams, cracks, and other defects in the surface, steps are taken and an apparatus provided in the practice of the present invention, by which combustible metal is heated at least to its ignition temperature and deposited substantially uniformly along a relatively long and narrow heated zone where the metal removal is to be started. While the com-

bustible metal is adjacent the heated zone and at a temperature which is at least its ignition temperature, a substantially continuous, wide stream of oxidizing gas is caused to impinge substantially simultaneously on both the heated zone and the combustible metal, in order to oxidize the latter so that the exothermic heat liberated by the oxidation quickly and uniformly raises to its ignition temperature at least a part of the heated zone against which the stream of oxidizing gas is directed.

As soon as the surface metal of the initial or starting zone against which the stream of oxidizing gas impinges, is raised to its ignition temperature, relative movement of the stream and the body is caused to take place, whereby a thin sheet or skin of metal is removed from the body or work, to leave a new, bright surface more or less free from checks, seams, cracks, and other defects according to the depth of the cut, or other manner in which the operation is carried out.

To this end there is provided, in accordance with the present invention, an apparatus having a number of blowpipes spaced closely enough together so that the streams of oxidizing gas merge to produce a wide, but transversely rather narrow, continuous stream of oxidizing gas. A suitably wide heating flame and wide oxidizing stream of gas can be produced by the wide mouth nozzle disclosed in application Serial No. 107,334, now United States Patent No. 2,267,405.

Associated with the blowpipe nozzles, there is provided a row of starting rods in position to deposit metal along the heated zone, together with mechanism for feeding the rods into the preheating flames and the oxidizing stream, preferably so that the metal is deposited along the heated zone only to thus expedite the start of the cutting operation at or during the start of the operation. The rods may be so closely spaced together, relative to one another, that the metal is deposited in a substantially continuous line or path along the heated zone. It has been found, however, that satisfactory starting is obtained over a relatively long, narrow starting zone in accordance with the present invention, when a starting rod is provided for each one of a number of nozzles as shown in Figure 1.

When a cut is started on cold work by causing a stream of cutting oxygen to impinge on a small globule of molten metal deposited on the work surface, the cut starts at the place at which the molten metal is in contact with the work surface. As relative movement of the stream and the work starts and the cut progresses, the molten metal and the slag resulting therefrom, spread over the work surface to broaden the cut. Usually about one or two inches of relative movement between the work surface and the nozzle is required for the cut to broaden to the full width normally cut by a single nozzle of the type shown in Figure 1. Where only one of a number of nozzles simultaneously employed, is provided with a starting rod positioned as in Figure 1, as much as about five to six feet of relative movement may be required for the entire cut to be widened to the full width normally cut by the row of nozzles. Accordingly, where it is desired that the cut be widened to the full width normally cut by a row of nozzles, preferably at least one starting rod is provided for each such nozzle. In other arrangements, such as those where nozzles having a wide mouth or slotted oxygen or pre-heating gas passages are employed, the starting material may be disposed and distributed along

the zone where the desurfacing operation is to be started in any manner desired for quick and efficient starting in accordance with this invention.

5 Feeding the starting wires or rods at an angle to the work surface has been found to give greater economy in the amount of wire used, as compared with feeding a length of wire substantially parallel to the work surface and extending along the heated zone. For instance, it has been found that when the starting rods are fed at an angle to the work surface, a total of about three inches in length of starting rod will suffice to start a cut about eight inches wide, as against eight inches of wire required if it is fed substantially parallel to the work surface and along the heated zone in the case of a row of nozzles of the type disclosed in Figure 1.

In removing a skin or thin layer of metal from various types of ferrous metal bodies or objects, in accordance with this invention, it may be desired to avoid removing metal from certain portions of the work while removing it from other portions, contiguous therewith, in accordance with some predetermined pattern. To this end certain of the nozzles of a row, or bank, may be blocked off, or the gas passages to them closed, or combustible metal for starting the cut may be supplied to certain of the nozzles at an appropriate time relative to the starting of the cut with other nozzles, as the case may be.

If a flame, such as a wide oxy-acetylene flame as may be used for heating the starting zone, is used for heating the oxidizable metal to its ignition temperature or for melting it, a very satisfactory material for starting the cut is a rod of iron, or an alloy high in iron. If, in starting a cut uniformly along a zone in accordance with this invention, a number of starting rods are 30 to be used along the zone, it is preferable that they be selected of sufficiently uniform size and composition for that purpose. Uniformity of the period of time required to heat the metal to its ignition temperature, or to melt it, and, accordingly, uniformity in starting the cut along the zone, is favored by uniformity of conditions with respect to size of the rods, intensity of the heating flame along the zone, and the like. For uniformly starting a cut along a wide zone with 35 a ferrous metal rod of circular cross section, a rod about $\frac{1}{8}$ inch in diameter is very suitable, although rods of larger or smaller diameter may be used. Such rods are relatively stiff and, when suitably disposed with reference to the work surface, may advantageously be fed by gravity.

Another shape of wire or rod, other than circular, which has been found to give satisfactory results is a flat, ribbon-like wire. Such a wire, having the same cross-sectional area, or yielding substantially the same quantity of combustible metal by incremental lengths introduced into the pre-heating flame, as a given circular rod, may be rolled into compact flat coils occupying a relatively small space. The flat wire is most readily melted by so feeding it into the flame that the flame impinges on the narrower side, or edge, of the wire. Edge feeding of flat wire has the advantage that the time normally required to melt an incremental length, or suitable end portion of the wire may be as little as three seconds or less. If desired, however, the flat wire may be so introduced into the heating flame that the flame impinges on the wide or broad side rather than upon the narrower side or edge. Feeding of the flat wire or rod so that the preheating flame im-

pings on its broad side, favors the widening of the cut to the full width normally cut by the nozzle, by tending to spread the flame and the combustible metal. In order to control undue spreading of the combustible metal which may be encountered under certain circumstances, it may be found expedient to use a somewhat greater thickness of rod than might otherwise be required, particularly in the case of flat wire which is introduced broadside into the flame. While the impingement of the heating flame on the broadside of the flat wire tends to widen the cut to the full width normally cut by the nozzle of the type illustrated in Figure 1, it does not necessarily follow that the cut is started in a shorter period of time, inasmuch as the time required to heat the metal to the ignition temperature is also an important factor. For the more rapid melting of the flat wire in a heating flame of a nozzle of the type illustrated in Figure 1, the preheating flames preferably impinge on the narrower edge of the flat wire or ribbon.

As has been set forth above, the conditions which determine the length of time required to heat the surface metal of the work to the ignition temperature may be so selected and established as to obtain a substantially uniform preheating time for work which is more or less alike, or along a zone where a cut is to be started. Accordingly, the preheating time can be predetermined with sufficient precision from the time the feeding and heating of the combustible metal is initiated until the surface metal of the work is heated to its ignition temperature, as to permit of automatic timing or measuring of the interval. At the end of the measured time or interval when the surface metal of the work is at its ignition temperature, the cutting oxygen valve may be automatically opened so that cutting oxygen is caused to impinge at or along the heated place when the cut is to be started, and relative movement of the nozzle and the work caused to take place automatically, as well. These automatically-operated mechanisms of the present invention may be placed under a common control which may cause the steps or cycles of the process to take place in a particular sequence upon a single actuation of the common control. On the other hand, each of the mechanisms may be provided with independent controls which, however, may also be adapted to cause the steps of the process to take place in a particular sequence upon simultaneous actuation of such independent controls.

Various types of interval timers or time delay devices may be used for measuring the preheating time, among which may be mentioned, by way of example, a synchronous electric motor, if suitable alternating current is available, a fluid escape device, a time delay relay and the like.

Referring again to the drawings, and more particularly to Figure 1, the desurfacing apparatus shown by way of example comprises a conveyor including a roll 6 driven by a motor 7 for positioning and propelling a ferrous metal body W, such as a steel billet, in a direction which may be substantially parallel to its top surface S. Supported (by suitable means, not shown) in a position above the path of such surface S of the work W, is a desurfacing unit H comprising a battery of deseaming nozzles 8 mounted in ports 9 of a shoe 10 adapted to rest lightly on the surface S. Each deseaming nozzle is supplied with a combustible preheating gas, such as a mixture of acetylene and oxygen, for discharge by an annular series of orifices 11, and an oxidizing gas, such as

oxygen, for discharge by a relatively large central orifice 12. These gases are delivered to the nozzles through suitable and conventional blowpipe means, not shown. Each of the gas supply conduits through which preheating oxygen, preheating acetylene, and cutting oxygen are separately supplied to such blowpipe means is provided with a normally-closed valve for controlling the supply of these gases. These normally-closed valves (not shown) in turn are adapted to be opened by electrical means, such as solenoids PH and CO of Fig. 7, upon energization.

The blowpipe unit H is provided with a number of rod guiding tubes 13, each of which is adapted to have a starting rod N slidably disposed therein. In Fig. 1, each tube 13 is shown so disposed that its downwardly extended longitudinal axis intersects that of the corresponding nozzle 8 at about the surface S of the work. Extending transversely of the tubes 13 and the starting rods N is a shaft 15 which is supported on the unit H. Mounted on the shaft 15 are fingers 16 corresponding, in number, to the tubes 13. Each of these fingers is so mounted on the shaft as to normally engage the rod N under the influence of a tension spring 17 which is anchored at its upper end to a cross bar 18, and connected at its lower end to the finger 16 through a hole 19. At the same time the fingers are so affixed to the shaft—as by a key, pin, set screw, or the like—as to turn with the shaft and be disengaged from the rods when the shaft is turned sufficiently. A certain degree of lost motion between the fingers 16 and the shaft 15 is provided to insure that each of the fingers will be free to engage the rod under the tension of its spring 17. Otherwise, if the fingers are attached so rigidly that there is no lost motion between them and the shaft, it would be necessary to set or adjust each of the fingers separately to compensate for any lack of uniformity as might exist in engagement between the fingers and the rods. Thus, the fingers 16 normally hold the rods N in elevated position above the work surface S. However, when the shaft 15 is turned through a sufficiently large angle, the fingers 16 release the rods N which then drop down under the influence of gravity until they rest on the work surface S.

By such a disposition of parts as has been described, and additionally as clearly shown by the drawing, it will be recognized that equal portions of equally spaced starting rods are advanced to a row of equally spaced heating jets and oxidizing jets adjacent a long and narrow starting zone; that the said portions of said rods are fed to said zone by a row of equally spaced starting rod feeding means in order to attain substantially uniform heating of said portions and also their substantially uniform oxidation in order to effect substantially uniform rapid starting of the conditioning operation at all points along said zone; and that preferably all of said rods are disposed in a plane which intersects the plane of the work surface along said zone, namely, the rods are in a plane transverse to the plane of the work surface.

At one end of the shaft 15 a crank 20 is attached, and this crank 20 is connected to a lever 21 by a link 22. The lever is pivoted to a vertical arm 23 of a bracket 24 mounted on the unit H, and is adapted to be operated by an armature 25 of a solenoid RF. The tension spring 26 normally supports the link 22 and the weight of the otherwise unsupported parts connected

thereto. When the solenoid RF is energized its armature 25 is pulled downwardly, actuating the lever 21, link 22, crank 20 and fingers 16 to release the starting rods N which drop until they rest on the work surface S.

If desired, the wire feeding mechanism shown in Fig. 4 may be used. In this mechanism, each starting wire K preferably is in the form of a flat ribbon fed from a spool or roll 21 on a shaft 28. Each starting wire K is caused to be positively fed into the preheating flame, when the solenoid RF is energized, by means of a lever 29 secured to the shaft 15 by a lock screw 30. At its end adjacent the starting wire K the lever 29 is provided with a clutch mechanism 31 including a self-locking detent 32, the arrangement being such that when the lever 29 is partly turned the detent 32 engages the starting wire K and advances the latter through a desired increment. When the solenoid RF is de-energized, the lever 29 with the clutch 31 is returned to its initial position by a tension spring 33. It is to be understood that a starting ribbon or wire K may be provided for each nozzle 8, the general arrangement being substantially like that shown by Fig. 1.

Still another modified form of wire or rod feeding mechanism is shown in Figure 5. The base or main member 101 is so mounted in or on the desurfacing machine that the wire is fed into the preheating flames so that the flames impinge on the narrow side or edge of the wire. In this modification, the starting rod or wire J is also preferably in the form of a ribbon although wire of other cross section, such as round wire, may be used. The wire J passes from the coil 102 through a movable wire gripper 103, a stationary wire gripper, or brake 104, and a guiding slot in the bar 100 to the deseaming nozzle. The movable wire gripper 103 is mounted on a movable member 105, which is, in turn, so mounted on the movable links 106, to form one side of a parallelogram linkage, that when the member 105 is moved, it moves substantially parallel to the direction in which the starting rod is to be fed. The movable member 105 is caused to move in a forward direction by a lever 107 which engages a projection 108 extending laterally from the movable member 105. The lever 107 is pivoted at one end on a pivot 109, secured to the back of the housing H. At the other end of the lever is an elongated opening or slot 110 for adjustably and pivotally connecting it to the link 111 at various distances from the pivot. If desired, a shaft similar to 15 may be used in place of the pivot 109 in which case two levers 107 may be keyed to the shaft, one lever at each end thereof, in position to engage projections 108 extending laterally from each side of the movable member 105.

Wire grippers 103 and 104 are of similar construction. Each comprises a body portion 112 (Fig. 6) and a cover 113 which are held together and fastened to the movable member 105, or the base 101 as the case may be, by bolts 114. As shown in Fig. 6, which is a section taken on line 6-6, a slot 115 is cut in the wire grippers for the flat wire or rod to pass therethrough. In the body portion of each gripper, there is a compression spring 116 tending to wedge a steel ball 117 between the wire rod and a race 118 in the block 112 disposed at an angle to the axis of the wire J. In both the movable gripper 103 and the stationary gripper 104, the ball, the spring, and the angular race are in similar positions relative

to the wire, in order that the wire may advance freely through the stationary gripper with forward motion of the movable gripper, and remain stationary during the reverse motion of the movable gripper.

In the stationary gripper, the ball and spring are in the position shown in Fig. 6 so that, when the wire J is advanced downwardly toward the preheating flames, the advancing wire moves through the gripper in a direction tending to compress the spring. Thus, the ball 117 in the stationary gripper does not wedge against the advancing wire, and the wire may be advanced freely therethrough. If the wire tends to move in the reverse direction, however, the spring 116 acts to aid the ball in wedging itself between the angular race and the wire thus to hold the latter stationary relative to the gripper 104 and the base 101. Any movement of the wire in the reverse direction assists the wedging action of the ball.

When the movable gripper 103 is moved in the forward direction (downwardly) the ball 117 in the gripper 103, assisted by the spring and the forward motion of the gripper 103, wedges itself between the race and the wire so as to grip and advance the latter.

When the movable wire gripper 103 moves in the reverse direction (upwardly) to return to its normal position, however, the stationary gripper 104 holds the wire stationary relative to the base, and a relative movement of the movable gripper 103 and the stationary wire results which is similar to that of the stationary gripper and the wire while the latter is being advanced. Such return movement of the gripper 103 along the stationary wire is in a direction tending to compress the spring. Thus, the ball does not wedge between the wire and the angular race, and the movable gripper 103 slides freely over the wire during the return movement.

Means are provided for feeding an increment of wire in a predetermined amount each time the lever 107 is actuated. An adjustable stud 119, with locking nut secured to the base 101 and positioned to contact the bottom end of the member 105, limits the forward, or advancing movement of the movable member 105 and the gripper 103. A long tiebolt 121, which has one end fastened to the movable member 105, passes through an upper portion 101a of the base 101. The other end of the tiebolt passes through a compressible spring 122 which tends to keep bolt 121 and movable member 105 in the normal upward or return position. The return movement of member 105 toward the normal position is limited by adjustable nuts 123 on the threaded portion of the tiebolt 121 below the upper portion 101a of the base. A corresponding adjustment of the movement of the lever 107 can be made, if desired, by adjusting the position of its connection with the link 111 at the slot 110 to a greater or less distance from the pivot 109.

The feeding action of the mechanism shown in Fig. 5 is as follows: When the actuating mechanism, through the lever 107 and the link 111, moves the member 105 forward from its normal position, the movable wire gripper 103 advances the wire J through the stationary wire gripper 104 toward the work. When the lever 107 permits the member 105 to return to its normal position through the action of the spring 122, the wire gripper 103 releases its grip on the wire J, and wire gripper 104 grips the wire and prevents its withdrawal away from the work with member

105. The wire grippers 103 and 104 and the guiding slot in bar 100 will tend to straighten the wire and remove kinks and bends therefrom. The movable member or plate 105 and the base 101 may be extended to provide space for additional wire grippers 103 and 104 and guiding bars 100. Thus, as many starting wires or rods may be fed as may be required for the number of deseamng nozzles provided, or the work at hand, or both.

If a number of flat coils are to be used in a position, relative to the feeding mechanism, similar to that shown for coil 102 in Figure 5, it may be desirable to stagger the coils one above the other, or to spread them out fanwise, as a matter of convenient arrangement. Another form of arrangement is to place the coils in a row, each coil positioned relatively to the feeding mechanism as shown in Fig. 4. For edgewise feeding of the flat wire into the preheat flame, it will be necessary in the latter arrangement for the flat wire to undergo a quarter twist (90° turn) before entering the grippers of the feeding mechanism of Fig. 5. If it is desired to feed the flat wire broadside into the preheating flame, with the mechanism of Fig. 5, the guiding slot in the bar 100 may be so positioned and arranged as to impart a quarter twist (90° turn) to the wire. Alternatively, the flat wire may be fed broadside into the flame, with a feeding mechanism similar to that of Fig. 5, without the necessity of imparting a twist to the wire by so constructing and arranging the movable gripper 103, the stationary gripper 104, and the bar 100 that the flat wire passes through each with its broader side parallel to the front surface of the base H.

The cycle of operations for a desurfacing machine that is provided with a starting rod feeding mechanism as described, and with electricaly operated controlling devices wired as shown schematically in Figure 7, may be regarded as involving a number of main or principal steps. Before beginning the desurfacing step itself—i. e. the actual removal of metal from the work surface—the work W is positioned relatively to the desurfacing unit H so that the nozzles 8 will operate over the portion of the work surface S to be desurfaced. This positioning is accomplished by manually operating a master switch, which according to the direction in which it is thrown, causes the work-driving motor 7 of the apparatus of Figure 1 to move the slab W either forward or backward, as the need may be. If desired, however, the desurfacing unit H may be supported as by a carriage to be moved relatively to the work W which then remains stationary during the desurfacing operation. In either case, additional means (not shown) may be provided to assist in transversely adjusting the desurfacing unit H and the work W relatively to one another.

If the apparatus has been inactive for an appreciable period of time, it is preferable before beginning the desurfacing step to purge the gas supply conduits, including headers, of any contaminating air which may have seeped into them during such periods. It is preferable also to adjust the preheating flames and to set the proper cutting oxygen pressure prior to positioning the work relative to the desurfacing unit. The purging of the conduits and the adjustment of the preheating flames may be accomplished with the aid of a manually-operated purging switch having a first position which holds open the preheat valves, and (in addition to an off-position) a second position which holds the preheat valves

open and additionally opens the cutting oxygen valve. If the apparatus is in more or less continuous operation, however, it should be unnecessary to purge the conduits before carrying out a desurfacing operation. Similarly, the readjustment of the preheat flames or resetting of the cutting oxygen pressure should not be necessary before each desurfacing step is carried out on similar work, or the like.

10 It is preferred, for reasons of economy in the consumption of the preheating gases, that the preheating flames be so adjustd that their heating intensity is insufficient to heat the starting zone to the ignition temperature quickly, but rather of sufficient intensity to continue the operation in the desired manner once it has been started by the addition of the supplementary heat generated by the oxidation of the molten or highly heated starting material deposited on the surface in accordance with the present invention.

15 The desurfacing step itself may be started as soon as the desurfacing unit is in proper position relative to the work surface. In accordance with the present invention, the desurfacing may be carried forward by the simple act of depressing a push button. This causes the preheat valve to be opened, and the resulting combustible gas jets, discharged by the preheating orifices 11 of the nozzles 8, are ignited by any suitable means, such as a small pilot flame, not shown, or by the heat of the work surface itself if a hot billet is to be conditioned. At the same time the preheating gases are turned on, the starting wire or rod feeding mechanism is automatically actuated and the rods 14 or wires K or J are introduced into the preheating flame and properly positioned in front of the nozzles. Simultaneously, a time delay relay is energized, and at the end of a predetermined interval of time, during which the starting rods or wires are being raised at least to the ignition temperature, or even melted, the cutting oxygen valve is opened and the motor controller is actuated, driving the work W forward and resulting in a progressive desurfacing process over successive zones or areas.

20 When the end of the area to be desurfaced has been reached, depressing either another push button, or throwing the master switch into either a forward or reverse position, causes all of the gases to be shut off and the process to stop. If the operation has been stopped by means of the master switch, the work W itself will continue to be moved in the direction of travel determined by the position of the switch, until stopped by returning it to the off position. Further desurfacing can be accomplished by a repetition of the above procedure. Should it be desired to carry on the desurfacing manually, without the rod feed, this can be accomplished by positioning the work as before, then moving the purging switch into its first position for preheating. When this is accomplished, the desurfacing is carried out by simultaneously throwing the purging switch into its second position, and throwing the master switch to its forward position. At the conclusion of the desurfacing operation the purging switch is released and movement of the work W is governed through the master switch.

25 The electrical circuit, Figure 7, preferably comprises a pair of conductors L1 and L2 that are connected to a direct current power supply by line switch 36 through safety fuses 37. When

the purging switch PS is moved to the first or preheat position, its normally-open contacts PS-1 are closed and a circuit is established from conductor L1 to conductor L2 through said contacts PS-1 of the purging switch, and a preheat relay winding X. The relay winding X thus is energized and opens the preheating gas valves by closing normally-open contacts XC in a circuit which includes the preheat valve solenoid PH. When the purging switch is advanced to its second or cutting position, its normally-open contacts PS-2 are closed, thereby energizing a circuit which includes the solenoid CO controlling the cutting oxygen valve.

Positioning the work W preferably is accomplished by the manual operation of the master switch MS having normally-closed contacts MS-C, and normally-open contacts MS-F and MS-R. The normal position of this switch is in the off or neutral position. The other two positions, one on each side of the center, are for controlling the direction of travel of the work W. The normally-closed contacts MS-O are opened when the switch is in either the reverse or forward position. The contacts MS-F are normally open, but are closed when the master switch is thrown into the forward position. The contacts MS-R also are normally open, but are closed when the master switch is thrown into the reverse position.

When this positioning master switch is thrown into the forward position, the contacts MS-F are closed and a circuit is energized which includes a normally-closed switch 35 controlled by a stop push button S-PB, a normally-closed reverse relay switch R1, a forward relay winding F, a normally-closed travel-limiting switch 42, and normally-closed accelerating relay auxiliary contacts IAC.

When the forward relay winding F is energized through the above circuit, the motor 7 is started by means of a circuit including normally-open forward relay contacts FC of the relay F, which are now closed, the motor armature A, normally-closed reverse relay contacts RC, a portion R2 of a dynamic braking resistor 46, a field fluttering contact relay coil FA, and a starting resistor 47. The accelerating relay winding IA is connected in parallel with the armature A of the motor 7. As the motor accelerates, the voltage across its armature A will increase. When it reaches the value for which the accelerating relay has been set, its normally-open switch IAS will close, thus short circuiting the starting resistor 47, and connecting the coil FA directing to conductor L2. Its auxiliary contacts IAC, in the circuit of the forward relay winding F will open, introducing resistor 51 in series in the forward relay circuit. This is done because the coils of the forward and reverse relays are not designed to operate continuously at full line voltage.

The field circuit 52 of the motor 7 is energized through three substantially independent circuits, and is so designed as to give sufficient field excitation and thus good acceleration regardless of the setting of a field rheostat 53. Since the motor 7 is shunt wound, the armature starting current and torque are dependent upon the field current; but due to prior setting of the desired desurfacing speed, this field excitation might be extremely low and consequently poor starting would result. In addition, for best results when using dynamic braking, some field excitation must be obtained. These features all are pro-

vided for as will be shown in the following description.

With an established circuit including normally-closed auxiliary accelerating relay switch IA2, and the motor field winding 52, full field excitation is provided during the starting period. After the motor has accelerated to the point where the accelerating relay winding IA is energized, its auxiliary contacts IA2 open. When this occurs there is energized a circuit including the field rheostat 53, normally-closed quick return contacts CR1, CR1 and the motor field winding 52. This sudden change of field current will cause the armature current (and hence the torque) to rise to higher values, consequently increasing the motor speed. This increase in armature current causes the field fluttering relay winding FA to close normally-open contacts FAC which are in parallel circuit relation with the auxiliary accelerating relay switch IA2, the field rheostat 53 thus being short circuited. The subsequent increase of speed and decrease of armature current will cause the motor field fluttering or accelerating relay winding FA again to drop out, and the previously-described process will continue to take place until such time as the armature A of motor 7 has come up to the preset speed.

When the positioning master switch is returned to the off position, which occurs when the machine is to be stopped, the forward relay winding F will be de-energized because its circuit will be opened by the forward contacts MS-F of this switch. The main forward relay contacts FC thereupon open the circuit including the terminal A1 of the motor armature, but in so doing, normally-closed forward relay contacts FC1 of the relay F again close, applying the dynamic braking through the local circuit comprising resistor 46 and the normally-closed reverse relay contacts RC.

A minimum field excitation for the dynamic braking is necessary and is obtained through the circuit including normally-closed auxiliary reverse relay switch RS, a normally-closed auxiliary forward relay switch F1, a tap 57 on the rheostat 53, normally-closed quick return relay contact CR1, and the field winding 52 of the motor 7.

When it is desired to reverse the direction of travel of the work W, the positioning master switch is moved to its reverse position; whereupon there is established a circuit including the normally-closed stop push button switch 35, the closed reverse contacts MS-R of the master switch, a normally-closed auxiliary switch F2 of the forward relay, the coil R of the reverse relay, final limit switch 42, and switch IAC of the accelerating relay. In parallel circuit relation with the reverse relay coil R is the quick-return relay coil CR, and a protecting resistor 62, of the quick-return relay, which is useful when the head H is operated relatively to stationary work, but which may be omitted when the work itself is moved only in one direction. This quick-return relay is energized at the same time that relay coil R is energized.

The reverse direction of rotation of the armature A of the motor 7 is accomplished upon the energization of a circuit including the normally-open but now closed contacts RC1, through the armature A in the direction from terminal A2 to terminal A1, normally-closed main contacts FC1, resistor portion R3, the relay coil FA and the accelerating resistor 47. The field flutter-

ing relay winding 1A will cause such relay to act as before, except that for the reverse direction, when no desurfacing is being done, the highest speed is desired, and is obtained independently of the setting of the rheostat 53 by means of the quick-return relay CR. This high speed return is obtained by energization of the quick-return relay CR. Upon energization of the relay CR the contacts CR2 close, short-circuiting the rheostat 53, and contacts CR4 open, thereby introducing a resistance 71 into the circuit including the motor field winding 52.

With the desurfacing unit H positioned over the work W to be desurfaced, simply depressing the starting push button PB, or 34, will cause the entire operation automatically to proceed, because there is energized a circuit including the normally-closed switch 35, the normally-closed contacts MS-O of the master switch which must be left in the off position, the push button switch 34, or PB, and the preheat relay winding X. Energizing relay winding X causes the contacts XC to close and thus energize the circuit including the solenoid PH which thereupon opens the preheating gas valves. Relay X, when energized, also causes a bridging circuit around PB (34) to be completed. This bridging circuit includes the contacts X1 (of relay X), contacts PS-A of the purging switch PS, which contacts are normally closed when the purging switch is in the off position, and relay coil X.

Simultaneously, the rod feed relay coil Y is energized through a circuit including contacts PS-B of the purging switch, a normally-closed switch TD2 of the time delay relay and relay coil Y.

This causes normally-open contacts YC to close and energize the rod feeding solenoid RF, thereby causing a measured length of starting wire or rod (K, J or N) to be introduced into the preheating flames discharged by the nozzles 8. When the solenoid armature 25 has completed its downward travel, normally-closed switch RFC is mechanically opened by said armature 25, and a resistor 68 is inserted in the circuit of the solenoid RF. This feature is necessary because the solenoid RF is not designed for continuous operation at 230 volts, the preferred voltage of the power circuit.

The third simultaneous operation that takes place when the cut is started by means of the starting push button PB, is the initiation of a predetermined time relay period by the energization of a circuit including the coil TD of the time delay relay. The energization of this timing relay coil TD is adapted preferably to remove a restraining force on a mercury dashpot mechanism, for example, which controls the contacts TD1, TD2, and TD3 of the timing device. At the expiration of the metered time interval, the cutting oxygen valve is opened, the work is started forward, and the rod feed solenoid RF is de-energized.

The cutting oxygen valve is opened through the closing of the circuit including the main preheat relay contacts XC, time delay relay contacts TD3 and the cutting oxygen valve solenoid CO. The work W is propelled forward by the motor 1 which is energized when the circuit including relay contacts TD1 is energized, as described previously in connection with the forward travel of the motor. The circuit for the rod feed solenoid RF is de-energized by the opening of the contacts TD2 of the time delay

relay in the circuit including the rod feed relay coil Y. When this relay coil Y is de-energized, its main contacts YC open the circuit including the rod feed solenoid RF.

As pointed out above, when starting a cut, the desurfacing head H is positioned above the surface S of the work W and the starting rods or wires are fed, or dropped until stopped by the surface of the work. The preheating gases melt the lower ends of the rods or wires and the cut is started automatically in approximately or slightly less than three seconds at any desired point on the surface of the work. Simultaneously with starting the cut, or slightly before, the solenoid 25 is de-energized and the rods are secured so that they cannot feed downwardly, as shown in Figure 2.

While the invention has been disclosed in connection with the art of desurfacing, it will be understood by those skilled in the art that it is applicable to other processes involving the thermochemical conditioning of ferrous metal, such as gas severing and metal treatments involving the combustion of metal.

The disclosed apparatus is automatic in operation and for this reason the cost of desurfacing is reduced while at the same time gouging is eliminated, which results in improving the desurfaced article.

What is claimed is:

1. A method of thermochemically desurfacing a relatively wide surface area of a ferrous metal body, such as a steel bloom, billet, or slab, in a single pass of said body relatively to a thermochemical desurfacing means, such method comprising heating a relatively long, narrow starting zone extending across said surface area; heating oxidizable metal at least to its ignition temperature adjacent to and along said zone and simultaneously depositing such heated metal at a plurality of closely spaced places throughout the length of said zone; simultaneously directing a plurality of separate jets of oxygen obliquely toward said starting zone and the hot metal deposited therealong, said jets being so spaced and positioned relative to each other as to merge to form a continuous wide stream extending throughout the length of said starting zone, and said jets and said places of metal deposit being so spaced along said starting zone that each of said separate jets is directed against one of said deposits of heated metal, to burn said hot metal and thereby produce enough exothermic heat to quickly raise to its ignition temperature the adjacent portion of said surface area; and thereupon causing movement of said body relatively to said wide stream while directing the latter against said surface area to progressively de-surface said surface area.

2. A process of initiating the thermochemical reaction between a body of ferrous metal and a plurality of jets which merge to form a substantially unitary stream of cutting oxygen movable relatively to said body so as to react thermochemically with an initial and successive zones along the surface of said body, comprising introducing a plurality of combustible ferrous metal starting rods into the region of said initial zone and into the path of said stream of cutting oxygen; preheating a portion of each of said rods to the combustion temperature for reaction with said stream, the heat generated by said reaction assisting in preheating said initial zone for reaction with said stream; and so coordinating the steps of said process that said

stream of cutting oxygen is turned on and such relative movement initiated at an automatically metered time interval subsequent to the time that said preheating operation is commenced, said metered time interval being determined by the period required to preheat said rods to the combustion temperature.

3. A process of thermochemically conditioning a substantially wide surface of a ferrous metal body which comprises directing a wide heating medium against a surface of said body to provide a relatively long but narrow heated starting zone extending across the surface; so introducing the ends of a plurality of spaced, ferrous metal starting rods in the form of flat wires or ribbons into the heating medium at the start of a conditioning operation that a small portion of each wire is heated to at least the ignition temperature, said wires being inclined to said surface of the body and also being so positioned that such heated portions are located at a plurality of closely spaced places along said zone; impinging a wide stream of oxidizing gas against such heated wire portions and also against the heated surface metal along said zone; and thereupon moving said body and said oxidizing gas stream relatively to each other in such a direction that said stream progressively thermochemically conditions successive portions of said surface of the body.

4. Apparatus for thermo-chemically conditioning ferrous metal bodies comprising a blowpipe including a nozzle for directing a heating medium against an area of an upper, substantially horizontal surface of such a body to provide a heated starting zone and also for directing an oxidizing gas jet against said heated zone; means for effecting relative movement between said body and said blowpipe in a direction generally parallel to said surface; means for guiding a starting rod of ferrous metal downwardly into the region of said zone where a portion of said rod may be heated by said medium and oxidized by said gas; means normally maintaining said rod in a fixed position relative to said blowpipe and said surface; and means for momentarily releasing said rod whereby said rod descends along such guiding means and under the influence of gravity until its lower end engages said surface.

5. In an apparatus for thermo-chemically conditioning ferrous metal work such as a steel billet, means providing a stream of cutting oxygen directed against a zone extending transversely of the length of a surface of the work; means providing a preheating flame directed against said zone; propelling means for effecting movement of the oxygen stream along said surface relatively to the work; valves for separately controlling the oxygen stream and the preheating flame; feeding means for feeding starting material into the preheating flame; and common control means which, in response to actuation, is operative automatically in sequence to both open the preheat valve and to operate said feeding means, and subsequently to open the cutting oxygen valve and to operate said propelling means.

6. Apparatus according to claim 5, in which the common control means includes a time delay means which causes the opening of the cutting oxygen valve to occur at the end of a fixed time interval after the feeding of said starting material.

7. A process as defined in claim 3 in which the

heating medium is a heating flame and the flat wires or ribbons are so positioned relatively to the heating flame that the heating flame impinges on the narrow side or edge of each of said flat wires or ribbons in order the more quickly to initiate the melting of the wires or ribbons.

8. A process as defined in claim 3 in which the heating medium is a heating flame and the flat wires or ribbons are so positioned relatively to the heating flame that the heating flame impinges on the broad side of each of said flat wires or ribbons in order the more quickly to widen the cut to the full width normally cut by the oxidizing gas.

9. Apparatus for thermo-chemically conditioning ferrous metal bodies, such as steel billets, comprising a blowpipe unit; means for propelling a body in a direction generally parallel to an upper surface thereof and under said blowpipe unit; said blowpipe unit comprising means for directing a heating medium against said surface to provide a starting zone extending transversely of the direction of movement of said body, and means for directing a row of spaced oxidizing gas jets obliquely against said surface in the region of said zone; guiding means, associated with said blowpipe unit, for guiding a row of spaced starting rods of ferrous metal downwardly into the region of said zone, said guiding means being so constructed and arranged that said rods will descend along the guiding means under the influence of gravity; means normally holding said rods in fixed position relatively to said blowpipe unit; and means for substantially simultaneously releasing said rods to permit the rods to descend in unison by gravity until their lower ends rest closely adjacent said zone where small portions of said rods may be uniformly heated by the heating medium and oxidized by the oxidizing gas.

10. Apparatus for working ferrous metal, comprising, in combination: a blowpipe unit provided with preheat means for directing a relatively wide heating medium against a work surface to provide a relatively long, narrow heated starting zone extending transversely of the length of such surface; means, responsive to the initiation of said preheat means, for feeding a measured quantity of ferrous metal in the region of said zone, where it is melted by said heating medium and deposited on the work surface heated by said medium; said blowpipe unit being provided with means for directing a relatively wide stream of oxidizing gas against said work surface in said zone; automatic time delay means acting to start the flow of said oxidizing gas at the end of a fixed time interval after the feeding of said ferrous metal to said zone; and propelling means, responsive to the starting of said flow, for moving said blowpipe unit relatively to said work in a direction substantially parallel to such work surface so that a wide layer of metal is removed therefrom by said oxidizing gas means.

11. In an apparatus for conditioning work such as billets, means for delivering a stream of cutting oxygen of a substantial width against one surface of the work, means providing a gaseous preheating flame substantially coextensive with said stream, means for effecting movement of the work and the oxygen stream relatively to each other; separate valves for controlling the oxygen for said stream and the gas for the preheating flame; feeding means for

feeding starting material into the preheating flame; and control means which, in response to actuation, is operative automatically in a predetermined sequence to both open the preheat gas valve and operate said feeding means, to open the cutting oxygen valve, to operate said means effecting relative movement of the work and the oxygen stream, and finally to stop said movement and restore said control means to its initial condition for a repetition of said predetermined sequence.

12. Apparatus according to claim 11 in which the common control means includes a time delay means which causes the opening of the preheat gas valve and the operation of the movement effecting means to be successive.

13. Automatic apparatus for thermochemically removing a layer of metal from at least one surface of a ferrous metal billet, bloom, slab and the like, which comprises, in combination: a plurality of spaced means for severally delivering streams of oxygen gas flowing at relatively low velocity, and of high-temperature flame-producing gas, said means being adapted to deliver such streams of said gases obliquely against such surface and in initial and successive zones of a substantial length extending transversely thereof a dimension of said surface; means for feeding starting material adjacent to and along such initial zone and into the flame of such high-temperature flame-producing gas; valves controlling said oxygen gas and such flame-producing gas; means for effecting movement of said body and said gas delivering means relatively to each other; and common means for controlling the opening of said valves, the operation of said starting rod feeding means, and the operation of said movement effecting means.

14. Apparatus for carrying out a desurfacing operation on ferrous metal bodies comprising, in combination: a blowpipe adapted to have such a body placed adjacent thereto and in position for having surface metal removed therefrom, said blowpipe having at least one cutting oxygen orifice and one or more preheating jet orifices associated therewith for impinging cutting oxygen and preheating flames against an area on the surface of said body so as to perform desurfacing operation; valve means for controlling the supply of cutting oxygen; means for so imparting relative movement of said blowpipe and such body that gas issuing from the cutting oxygen orifice of said blowpipe means will impinge on the surface of said body at a substantially uniform distance from said cutting oxygen orifice and at an angle to said surface during such relative movement; means for feeding a starting rod in front of the preheating orifice where the preheating flames will impinge upon a portion of the metal of said rod to be melted from said rod, said means for feeding the rod being so constructed and arranged that molten metal from said rod will be deposited on the surface of such body at a place where the cutting oxygen may impinge on it to oxidize it while the metal thus deposited is at its ignition temperature; and common control means, including a time delay mechanism, said common control means being arranged to operate in response to actuation at the start of a desurfacing operation to cause one or more starting rods to be fed into the preheating flames and after a predetermined interval to cause the cutting oxygen valve to be opened and relative movement

of the blowpipe and the body so to take place that the region of impingement progresses along the surface of the body in the general direction of the flow of the cutting oxygen whereby the flowing gas tends to move the molten slag and molten metal ahead of said region.

15. An apparatus as defined in claim 14 in which the blowpipe is provided with a row of cutting oxygen jet orifices so spaced and arranged relatively to one another that the gas issuing therefrom will merge into a substantially continuous flow extending along the region where the gas impinges on the surface of a body positioned adjacent the blowpipe for a cutting operation.

16. Apparatus for conditioning metal comprising, in combination, blowpipe means adapted for directing against a zone extending along a surface of metal work to be conditioned a stream of oxidizing gas, and a relatively wide heating medium of sufficient intensity to raise a small amount of combustible metal almost instantly to its combustion temperature; guiding means adapted to have a plurality of combustible metal rods slidably disposed therein substantially parallel to one another in such manner that the ends of the rods may be positioned substantially uniformly along such zone where a short length at the end of each rod may be heated at least to its combustion temperature, said guiding means being so constructed and arranged that the metal rods are also disposed at such an angle to the horizontal that the rods may slide freely under the influence of gravity; and rod holding means normally engaging the rods to keep them from sliding.

17. Apparatus for thermochemically conditioning a ferrous metal body such as a steel bloom, billet, slab and the like, said apparatus comprising, in combination, a thermochemical conditioning device having nozzle means constructed and arranged to deliver a gaseous heating medium adapted to heat a starting zone on a surface of the body; feeding mechanism for feeding fusible and oxidizable metal into the region of the nozzle means for heating by the heating medium; said nozzle means also having provision for delivering a stream of a gaseous oxidizing medium; means for separately controlling the heating medium and the gaseous oxidizing medium; propelling means for effecting movement of the body and said stream relatively to each other; and control means which, in response to actuation, is operative automatically in a predetermined sequence to turn on gas for the heating medium, and subsequently to turn on the oxidizing medium and also to cause said propelling means to operate.

18. Apparatus for thermochemically conditioning a ferrous metal body such as a steel bloom, billet, slab and the like, said apparatus comprising, in combination, a thermochemical conditioning device having nozzle means constructed and arranged to deliver heating flames, adapted to heat a starting zone on a surface of the body; feeding mechanism for feeding fusible and oxidizable metal into the region of the nozzle for heating by the heating flames; said nozzle means also having provision for delivering a stream of a gaseous oxidizing medium; means for separately controlling the heating flames and the gaseous oxidizing medium; propelling means for effecting movement of the body and said stream relatively to each other; control means which, in response to actuation, is operative au-

automatically to turn on the oxidizing medium and to cause said propelling means to operate after said heating flames have been turned on and said metal has been fed by said feeding means.

19. Apparatus for thermochemically conditioning ferrous metal bodies, such as steel billets, comprising a blowpipe unit; means for causing relative movement between the metal body and said blowpipe unit in a direction generally parallel to a surface of the metal body; said blowpipe unit comprising means for directing a relatively wide heating medium against such surface to heat a relatively long and narrow area to provide a long and narrow starting zone extending transversely of the direction of movement of said unit, and means for directing a row of spaced oxidizing gas jets obliquely against said zone; means, associated with said blowpipe unit, for guiding a row of spaced starting rods of ferrous metal into the region of said zone for heating a small portion of each of the rods at the ends thereof by said medium; rod-feeding means for advancing said rods along such guiding means toward said zone; and motion-transmitting means for operating said rod-feeding means to advance said rods simultaneously into the region of said zone for uniform heating of said portions.

20. Apparatus for thermochemically desurfacing a relatively wide surface area of a ferrous metal body, such apparatus comprising, in combination, a single blowpipe unit carrying a plurality of nozzles constructed and arranged to deliver a heating medium adapted to heat a portion of said surface area to provide a narrow heated starting zone extending across the width of said surface area; and rod-feeding means comprising a row of guides carried by said blowpipe unit in fixed relation to said nozzles and arranged to be aligned with said starting zone, said guides being constructed and arranged to guide and position the ends of a row of rods of oxidizable metal adjacent said zone, whereby the end portions of said rods are melted by said medium and deposited along said zone; said nozzles also having provision for delivering a wide stream of oxygen against said zone and against such deposited metal for removing a layer of surface metal substantially uniform in depth, such deposited metal being burned by said stream of oxygen and thereby producing enough exothermic heat to quickly raise to ignition temperature all portions of said zone throughout the width of the latter.

21. Apparatus for thermochemically conditioning a surface of a metal body such as a steel billet, comprising a blowpipe unit; means for causing relative movement between the metal body and said blowpipe unit in a direction generally parallel to said surface of the metal body;

said blowpipe unit comprising means for directing a relatively wide heating medium against such surface to heat a relatively long and narrow area thereof to provide a long and narrow starting zone on said surface extending transversely of such direction of relative movement, and means for directing a row of equally spaced oxidizing gas jets obliquely against said zone; means, associated with said blowpipe unit, for guiding a row of equally spaced starting rods of ferrous metal into the region of said zone for heating a small substantially equally sized portion of each of the rods at the ends thereof by said medium; rod-feeding means for advancing an equal amount of each of said rods along such guiding means toward said zone; and motion-transmitting means for operating said rod-feeding means to advance said rods simultaneously into the region of said zone for substantially uniform heating of said portions and for substantially uniform oxidation of said portions to effect substantially uniform rapid starting of the conditioning operation throughout the length of said zone.

22. Apparatus as defined in claim 21 wherein all of said rods are disposed in substantially the same plane, which plane intersects the plane of the work surface along said long and narrow starting zone.

23. Apparatus for thermochemically removing metal from a surface of a metal body, such apparatus comprising, in combination, flame-machining blowpipe nozzle means having combustible gas outlet means constructed and arranged to provide heating means to heat a relatively wide zone of said surface and also having oxidizing gas outlet means constructed and arranged to discharge oxidizing gas against such heated zone; and feeding means operable to simultaneously feed predetermined small amounts of fusible and oxidizable ferrous metal material to a plurality of regions longitudinally of said zone and in front of both said combustible outlet means and said oxidizing gas outlet means, whereby such oxidizable metal material is oxidized by said oxidizing gas to produce additional heat along said zone supplementing the heat applied along said zone by said heating means, and means for operating said feeding means.

24. Apparatus as defined in claim 23 wherein said feeding means includes a plurality of guiding means which are spaced substantially equal distances apart one from another, and wherein said amounts of oxidizable metal material are deposited separately but equally to said regions.
